UNITED STATES PATENT OFFICE

2,677,478

TANK

Thomas T. Woodson, Bridgeport, Conn., assignor
to General Electric Company, a corporation of
New York

Application January 14, 1950, Serial No. 138,663

1 Claim. (Cl. 220—5)

1 This invention relates to an improved tank and the method of constructing the same, and in particular relates to an improved end closure construction in tanks having an end wall or walls attached to a body wall in telescoping relation therewith.

Among the objects of my invention are to provide a method of construction which will substantially reduce material wastage in the fabrication of tanks and the like; which will provide a fluid-tight joint between the closure member and body wall without the necessity of accurately dimensioning the rim of the closure member with respect to the body wall; which lends itself to mass production with relatively simple tools and by unskilled labor; which will function effectively in the manufacture of irregularly shaped tanks; which will produce a tank or tub structure in which the relative thickness of the body wall and end walls may be as desired; and which is adaptable to various methods of manufacturing and physically joining the body and closure members.

My invention may be used in the fabrication of many types of low-pressure tanks or vessels. Certain of the advantages deriving from the use of the invention—for example those relating to material cost saving, and mass production with simple tools—are particularly important in the manufacture of washing machine tubs in the highly competitive and cost-conscious washing machine industry. The present methods of manufacturing washing machine tubs comprise variants of the basic technique of deep-drawing the tub and suspending it within an apron or mounting it on a wrap-around skirt. In the first of these, the apron provides external support for the tub and a decorative housing therefor; in the second, the tub may be exposed to view and the skirt simulates an extension of the tub while providing a supporting base. The waste in the drawing blank amounts ordinarily to about 33%, and for various reasons the rejects due to imperfections in the drawn tub are high. Also, it is entirely impracticable to attempt to produce a drawn tub having controlled or optional differences in thickness of the side wall relative to the bottom.

Briefly stated, a preferred method of practicing my invention comprises forming the body wall of the tub or tank by wrapping or rolling a rectangular blank into a cylindrical or prismatic form—in which latter term I mean to include polygonal shapes whose sides are not normal to the end surfaces—and joining the respective ends

5 by a simple structure such as a mash seam weld. I then provide a closure member having a rigid side rim configuration which provides a dovetailed space or pocket of which the body wall is an element. I prefer to spot weld the closure member to the body wall and accordingly the extreme outer dimension of the rim places the closure rim sufficiently closely against the body wall for welding thereto at relatively close intervals. A feature of particular importance in the manufacture of polygonal tubs is that the closure rim may be spaced from the body wall at the corner locations, thus eliminating the necessity of maintaining close dimensional tolerances at such locations. Whatever the tub shape, 10 the joint between the end and wall structures is made liquid tight by inserting within the dovetail space a distortable filler or gasket of rubber or other suitable material. Said gasket is of ring form so as to present no overlapping or butt joints along which leakage might occur. The insertion of said gasket may be accomplished after the 15 fabricated and mutually secured body and closure members have been given their protective or decorative finish. The body wall may provide the tub supporting structure, thereby eliminating the need for separate supporting means. If structural considerations so require, the body wall may be of heavier gauge than the closure member, or vice versa.

2 In the accompanying drawing, Fig. 1, is a side elevation, in section, showing one form of tank constructed pursuant to the present invention; Fig. 2 is a fragmentary side elevation similar to Fig. 1 with filler strip removed; Fig. 3 is a view similar to Fig. 2 but showing the filler strip in inserted position, said figure being taken on lines 3—3 of Fig. 4; Fig. 4 shows a plan view of a portion of the completed tank, the side wall being in section immediately above the filler strip; Fig. 5 is similar to Fig. 3 but showing a slightly different filler configuration; and Fig. 6 is a side sectional elevation of the filler strip of Fig. 5 showing its relaxed shape.

In Fig. 1, the tub 1 comprises a tubular body 2, a closure 3 secured internally thereof, and a filler strip or gasket 4 sealing the joint between the body wall and closure. In the open-topped tub shown, the closure forms the bottom thereof, but it will be understood that a similar closure may be applied at each end of the body wall, to form a closed-ended tank. As shown, the disposition of the closure 4 intermediate the ends of the body wall adapts the lower end of said wall as a supporting base to which legs or the

like may be affixed if desired. The body structure may be cylindrical or prismatic, as desired. When prismatic, as is frequently the practice in washing machine tubs, it is advantageous that corners between adjacent plane surfaces be somewhat rounded rather than sharply angular. The body structure may be seamless, or formed by wrapping or rolling a rectangular sheet on conventional metal working machinery. The wall material will be appropriate to the contemplated usage of the tub. My invention may, in fact, be used with wooden or other non-metallic structures. When of metal, the ends of the body sheet may be joined in any conventional manner; for example, by a mash seam weld (not shown). Where the tub is to be open topped, the upper edge may be rolled over or beaded as indicated.

The tub closure or bottom 3 also may be fabricated of any suitable material so long as said material will provide a rigid side wall or flange of necessary contour. The closure may be a casting or a molding; or, as will be most common, of drawn or stamped sheet metal, providing a relatively wide side wall or rim. By rolling or other conventional means, the rim is shaped to provide a bottom portion 5 which fits sufficiently snugly against the wall 2 at a multiplicity of points therearound to permit structural securement thereto, and an upper portion 6 inwardly offset from the rim 5 in angular relation therewith. Said upper portion cooperates with the body wall 2 and the web 7 to form a pocket in which the transverse dimension increases from the mouth of the pocket toward the bottom thereof. Figs. 3 and 4 show how the lower rim portion 5 and a portion of the web 7 may be cut away to provide the narrow gap 8, which thereby eliminates the necessity of a closely matching fit between the rim portion and the body wall. Such an arrangement is possible in my invention because the liquid-tight joint between the body wall and the closure is provided by the filler strip 4 and is not dependent on the means for physically attaching the closure member to the body wall.

The securement of the closure to the body wall may be by any means appropriate to the tub material or contemplated usage. In spot welding, it is desirable to apply a large area anvil against the outer wall and strike the welding electrode against the closure wall. The resulting weld joint is hardly discernible on the body wall. After the tub members have been assembled and secured, the desired exterior and/or interior finish may be applied.

The respective filler strips 4a are of a resilient material impervious to the material to be contained in the tub. The strip may be of extruded or molded material and is closed-ended. When relaxed, the filler strip should contact the inner wall of the tub throughout the periphery thereof. Its maximum transverse dimension, in section, should be greater than the maximum transverse dimension of the pocket, and its vertical dimension such that when the filler strip is placed within the pocket it will rest upon the base of the pocket and the distortion of the strip by the walls thereof will effect a substantial area of tight contact with the respective side walls of the pocket. It is most desirable that

the web 7 provide a continuous base at the corner areas of the tub wall. By soaping or otherwise lubricating the walls of the pocket, the filler strip may be manually inserted and driven home

5 within the pocket. The circular cross sectional shape of the filler strip shown in Fig. 2 will assume substantially the shape of Fig. 3 after the strip has been forced into the pocket. Where it is desired to produce a fillet at the edge of the 10 bottom member to avoid dirt-collecting pockets, a filler strip such as 4a, Fig. 6 will, when inserted produce the relatively smooth upper surface shown in Fig. 5. Filler strips may be removed and replaced without special tools, thus facilitating the maintenance or reconditioning of the 15 tank or tub.

While I have shown a particular embodiment of my invention, it will be understood, of course, that I do not wish to be limited thereto since many modifications may be made; and I therefore contemplate by the appended claim to cover any such modifications as fall within the true spirit and scope of my invention.

What I claim as new and desire to secure by Letters Patent of the United States is:

25 25 A receptacle for containing liquid having a shell of polygonal cross section; an end closure for said shell comprising a central portion of substantially the same polygonal shape as said shell but of smaller dimensions, side walls depending from said central portion at an angle approaching but not equal to a right angle, a rim extending from said side walls and closely approaching the inside walls of said shell along the rectilinear portions thereof while being spaced from said walls at corners, and flanges depending from said rim rectilinear portions; means for securing said end closure within said shell, portions of the walls of said shell along with said end closure side walls and rim defining 30 30 a pocket around the periphery of said end closure, said pocket having a maximum width at said rim and decreasing in width toward the mouth of the pocket because of the angular relation of said end closure side walls, and a continuous resilient and deformable band of a size and shape to fill completely said pocket and being insertable therein and removable therefrom without modification of the assembled position of said shell and end closure.
